US00D979503S

(12) **United States Design Patent** (10) **Patent No.:** **US D979,503 S**
(45) **Date of Patent:** **** Feb. 28, 2023**

(54) **INDUCTOR CORE**

(71) Applicant: **Crestron Electronics, Inc.**, Rockleigh, NJ (US)

(72) Inventor: **Robert Buono**, Ringwood, NJ (US)

(73) Assignee: **Crestron Electronics, Inc.**, Rockleigh, NJ (US)

(**) Term: **15 Years**

(21) Appl. No.: **29/801,331**

(22) Filed: **Jul. 28, 2021**

(57) **CLAIM**

The ornamental design for an inductor core, as shown and described.

DESCRIPTION

FIG. 1 illustrates a front perspective view of an inductor core showing the new design.

FIG. 2 illustrates a front view of the inductor core of FIG. 1.

FIG. 3 illustrates a back view of the inductor core of FIG. 1.

FIG. 4 illustrates a top view of the inductor core of FIG. 1.

FIG. 5 illustrates a bottom view of the inductor core of FIG. 1.

FIG. 6 illustrates a left side view of the inductor core of FIG. 1; and,

FIG. 7 illustrates a right side view of the inductor core of FIG. 1.
